UNITED STATES PATENT OFFICE.

JOHN NEIL, OF CLINTON, MASSACHUSETTS, ASSIGNOR TO "BIGELOW CARPET COMPANY," OF SAME PLACE.

DESIGN FOR CARPET.

Specification forming part of Design No. 5,188, dated August 8, 1871.

To all whom it may concern:

Be it known that I, JOHN NEIL, of Clinton, in the county of Worcester and State of Massachusetts, have invented a new and original Design for a Carpet, of which the following is a specification:

The nature of my design is fully represented in the accompanying photographic illustration, to which reference is made.

I claim as my invention—

The design for a carpet, as shown.

Witnesses:

CHR. G. STEVENS,

GEO. F. HASKELL.
